UNITED STATES PATENT OFFICE.

ARTHUR H. OCHS, OF LOUISVILLE, KENTUCKY.

SPARK-PLUG CONNECTOR.

1,154,201.

Specification of Letters Patent. Patented Sept. 21, 1915.

Application filed December 21, 1914. Serial No. 878,279.

To all whom it may concern:

Be it known that I, ARTHUR H. OCHS, a citizen of the United States, residing in the city of Louisville, county of Jefferson, and State of Kentucky, have invented a certain new and useful Improvement in Spark-Plug Connectors, of which the following is a specification.

This invention relates to spark plug connectors, and is intended particularly for use in connection with automobiles though it may be found of service in other places where a ready means of securing and releasing a circuit wire is desired.

An object of the invention is to provide a connector which will obviate the use of screws and nuts in the securing of a wire.

Another object is the provision of a connector which may be readily and firmly secured to a circuit wire and when so secured may easily be attached, with one hand to a spark plug, or other device.

With the foregoing and other objects in view my invention consists of the novel construction and arrangement of parts illustrated in the accompanying drawing, wherein is set forth an embodiment of the invention, but it is to be understood that such modifications and changes may be resorted to as come within scope of the appended claim.

Referring to the drawing wherein like reference characters designate like parts, Figure 1, is a side elevation of an embodiment of my connector in position on a spark plug. Fig. 2, is a perspective of the connector; Fig. 3, a perspective of the inner, or sliding member; Fig. 4, a perspective of the outer member; Fig. 5, a plan of the inner member; Fig. 6, a bottom plan of the outer member; Fig. 7, a diagram of the blank from which the outer member is formed; Fig. 8, a diagram of the blank from which the inner member is formed; Fig. 9, a perspective of the inner member.

Referring to the drawing —1— designates a spark plug of usual construction having a terminal projection —2— to which my improved connector —3— is affixed, the connector being secured on the end of a high tension electrical conductor —4—, such as is employed in automobile use, comprising a metallic wire, or strand, —5— surrounded by an insulating sheath —6—.

The connector 3 comprises a pair of suitably shaped, preferably rectangular, hollow

members —7 and 8—, the member 7 being adapted to slide within the other member. A pin —9— which passes through diametrically opposed openings —10—, —10'— positioned respectively in the upper and lower walls of the outer member and through corresponding slots —11— and —11'— in the inner member serve to retain the two members in operative relationship while permitting relative reciprocatory movement thereof. The inner member is divided by a longitudinal partition forming a compartment —13— within which is positioned an expandable coiled spring —14— which serves to keep the inner member at the outer limit of its movement. The inner member is provided with diametrically opposed perforations —15—, —15'—, in the upper and lower walls thereof, adapted, when the member is at the inner limit of its movement, to register with corresponding perforations —16—, —16'— in the outer member. The bottom —17— of the outer member is extended rearwardly forming a tongue —18— having a plurality of perforations —19— through which the bare wire 5 may be passed and secured. The tongue —8— has laterally extended ears —20— which are adapted to be clamped around the sheath 6, securing the connector rigidly thereto.

In using the connector it is taken between the thumb and second finger, pressure exerted, with the forefinger, on the outer end of the inner member forcing it inward as far as it will go, the connector is then positioned on the spark plug, with the terminal projection 2 extending through the aligned perforations —15—, —15'—, and —16—, —16'—, pressure on the inner member is then removed and the spring 14 forces the same outward, causing the opposing edges of the perforations to bind on the terminal 2, making electrical contact therewith and holding the connector firmly thereon.

Having thus described my invention so that anyone skilled in the art pertaining thereto may make and use the same, I claim:

A connector comprising a hollow outer member open at one end and having a plurality of diametrically opposed perforations in its upper and lower walls, a second member adapted to slide therein and open at its inner end, said inner member having a pair of diametrically opposed slots adapted to register with certain of said perforations, a pin passing through said registering slots

and perforations and adapted to hold said members in operative relationship while permitting relative longitudinal movement thereof, said inner member having a pair of 5 diametrically opposed perforations adapted to register with others of said first named perforations only when the members are in a given position, said inner member having a longitudinal compartment, an expansible 10 spring positioned within said compartment

and bearing respectively against the ends of said members, and a tongue extended from the rear of the outer member having means for the attachment thereto of an electrical conductor.

ARTHUR H. OCHS.
